DESIGN FOR AN ILLUMINATING CABINET

Arthur Gross Falk, Chicago, Ill.

Application October 16, 1935, Serial No. 59,013

Term of patent 14 years

To all whom it may concern:

Be it known that I, Arthur Gross Falk, a citizen of the United States, residing at Chicago, in the county of Cook and State of Illinois, have invented a new, original, and ornamental Design for an Illuminating Cabinet, of which the following is a specification, reference being had to the accompanying drawing, forming a part thereof.

In the drawing:

Figure 3 is a side view thereof, it being understood that the opposite side is the same as the side shown.

I claim:

The ornamental design for an illuminating cabinet substantially as shown and described.

Signed at Chicago, in the county of Cook and State of Illinois, this 11th day of September, 1935.

ARTHUR GROSS FALK.
